Cooperative Stove Company, Cleveland, Ohio

Application November 23, 1935, Serial No. 51,288

3 Claims. (Cl. 126—110)

This invention relates to an air heating and conditioning unit and particularly a unit of this character suitable for installation directly in the room to be heated.

One of the principal objects of the present invention is to provide a compact, simple and efficient air heating, conditioning and humidifying unit with cooperating means for circulating the air through the room or rooms to be heated, or supplied with conditioned air, in a manner such as to prevent stratification of the air in the room or rooms.

Another object is to provide a unit of this character which is enclosed in a compact and attractive casing and in which the heated parts are spaced from the casing and insulated therefrom by two sheets of air so as to prevent substantially any transfer of heat to the casing.

Another object is to provide a unit in which the vitiated air is continuously removed from the room and utilized for purposes of combustion.

Another specific object is to effect a directional discharge of the air from the unit whereby more effective circulation of air in the room or house is obtained.

Another object is to provide a unit of this character having a plurality of gas burners each of which, when operating, is operating at full capacity and in which part only or all of the burners are operable concurrently, for obtaining various heating stages.

A correlative object is to provide a proper correlation between the rate of discharge of air by the fan and the amount of heat supplied by the burners so that the temperature of the discharged air is more nearly uniform at the different rates of discharge of the air.

Other objects and advantages will become apparent from the following specification wherein reference is made to the drawings in which

Fig. 1 is a front elevation of a heating, humidifying, and air conditioning unit embodying the principles of the present invention, parts thereof being shown in section for clearness in illustration;

Fig. 2 is a rear elevation of the unit illustrated in Fig. 1;

Figs. 3, 4 and 5 are sectional views of the unit taken on planes indicated by the line 3—3, 4—4, and 5—5 respectively of Fig. 1;

Fig. 6 is a top plan view of the unit, part thereof being shown in section for clearness in illustration;

Fig. 7 is an electrical wiring and control diagram illustrating the manner in which safety in

operation and proper correlation between the various burners and fan are obtained.

Referring to Figs. 1 to 6 inclusive, the illustrative apparatus comprises a heat exchange head into which heating media are supplied by a number of gas burners, and through suitable heating tubes of which head air is blown by a fan. Part of the air, especially the slip stream from the fan, is passed through a suitable humidifying apparatus and then mixed with the air passed through the tubes of the heat exchange head.

For the purposes of illustration, a heat exchange head 1 of the type disclosed and claimed in the copending application of George Herbster, Serial No. 50,576, filed November 19, 1935, and better illustrated in Figs. 1, 2 and 3 hereof, is provided. The head 1 comprises an upright box-like structure, preferably having parallel front and rear walls 1a and 1b respectively and being sealed at the sides. A plurality of Venturi tubes 2 extend through the interior of the head and open through the rear and front walls, the tubes preferably being arranged in rows in staggered relationship with respect to each other so that heating media passing through the interior of the head are deflected by each tube in a manner to cause the heating media to pass around and into intimate contact with the wall surface of each tube. The tubes are so arranged that the openings through the walls 1a and 1b are disposed as closely together as possible so that substantially the entire front and rear wall surfaces in alignment with the fan, later to be described, are replaced by openings for admission of air to the tubes. This arrangement prevents undue back pressure on the fan when round tubes are used, but if more exposed wall surface is to be eliminated, the tubes may be square or hexagonal in cross section so as to fit even more closely together. The tubes 2 are Venturi tubes so that even with the large entrance and discharge openings, there is adequate space between the tubes within the heat exchange head 1 for the passage of heating media, and the resistance to the flow of air due to the contraction of the tubes is negligible.

The head is closed at the top by a suitable header 3, preferably of cast iron, which has a passage 4 for discharge of the products of combustion from the head 1. A supplemental detachable header 5 is provided also and forms with a portion of the header 4, an accumulator for receiving the products of combustion from the interior of the head 1 and for conducting the same into a flue 6 which, in turn, leads to

- a flue F of the room or compartment in which the unit is placed.
- For supplying heating media into the interior of the head, a plurality of gas burners are utilized.
- 5 The front and rear walls 1a and 1b of the head 1 and also the side walls depend from the head below the lower row of Venturi tubes 2 to form a combustion compartment 8 which is open at the top coextensive with the interior of the head 1 and is partially closed at the bottom by a suitable casting 9. Depending from the ends of the casting 9 are brackets 10 for supporting the burners and gas manifold, the brackets 10 tapering from their point of juncture with the casting 9 downwardly so as to converge toward the lower ends of the burners. Suitable side walls 11 may be provided on the brackets 10 and form a housing completely surrounding the lower portions of the burners.
- 20 A row of double head burners 12 are provided for supplying the heating media, these burners preferably being of the type described and claimed in the copending application of George Herbster, Ser. No. 50,575, filed Nov. 19, 1935. The burners 25 are arranged in a row extending transversely of the heat exchange head. As more fully described in the copending application, each burner comprises a pair of twin heads 12a arranged to discharge upwardly and mounted on a common body portion 12b, the body portion, in turn, being superimposed upon a suitable flaring mixing tube 13 which terminates at its lower end in a mixing bell 14. The burners are arranged in pairs, the pairs being connected by suitable heat radiating fins 15 formed integral with and connecting the mixing tubes 13 thereof. The outer ends of each pair of burners are provided with suitable fins 16 by which the pair of burners can be connected to each other in accurate alignment. The heads 12a 30 of the burners are spaced apart so as to permit entrance of air therebetween and the fins 16 are so arranged that adjacent burner heads of adjacent pairs are likewise spaced apart to permit the passage of air therebetween as better illustrated in Fig. 1. The burners are thus secured in a row and the end burners of the row, in turn, are secured to the brackets 10 so as to accurately position the burners. Each bracket 10 carries a depending portion 10a to which is secured a main supply gas manifold 18, the gas manifold, in turn, being provided with a plurality of gas discharge nozzles 19, one for each burner. The nozzles 19 discharge axially of the mixing tube toward the burner heads so as to prevent impingement of the discharged gas on the side walls of the associated mixing tube. A door 20 is mounted on the front wall 1 of the compartment 8 to permit access to the burners for cleaning and lighting. The bottom row of Venturi tubes 2 is spaced a sufficient distance above the burners to prevent impingement of the burner flame thereon. Space is provided between the side and end walls of the compartment 8 and the burners to permit access of secondary air to the burner heads.
- 65 The head 1 is preferably formed in two sections, the upper section being of sheet aluminum and the lower section being cast iron so that the heating of the air is substantially the same at all portions of the head, even though the lower rows of tubes 70 are subjected first to the heating media.
- In order to blow air through the tubes 2, a motor driven propeller fan 25 is mounted in spaced relation to the rear of the head 1. The fan 25 is driven by a suitable motor 26 which, as better illustrated in Figs. 2 and 3, is mounted on an up-

right bracket 27. The bracket is secured to a suitable support through the medium of legs 27a which are bolted to the support by upright bolts, so that, upon removal of one bolt only, the entire bracket, with the motor and fan, can be swung around the other bolt to permit access to the fan and to the interior of the unit.

5 In order to prevent vibrations of the motor from reaching and causing harmonic vibrations of parts of the unit, the bracket 27 is provided, at its upper end, with yoke arms 27b with which cooperate a yoke 28, the yoke arms and yoke defining an embracing support of greater diameter than the motor 26. Suitable rubber or resilient pads 29 are interposed between the motor and the yoke and yoke arms for resiliently supporting the motor.

10 In the plane of the fan 25 is an end wall 30 having an annular passage 30a in which the fan 25 is disposed, the wall 30 being spaced to the rear of the heat exchange head 1. The wall 30, in turn, forms the rear wall of an air chamber 31 having a top wall 32 and side walls 33, this chamber 31 being uncommunicated with the interior of the heat exchange head 1 and the burner 25 compartments and lower part of the main casing, later to be described so that the fan will not affect the air supply to the burners. In the chamber 31 in spaced relation to the head 1 and to the side and front walls of the chamber 31 is a baffle wall 34, having a passage 34a permitting access to the door 20, the wall 34 being open at the rear providing an air inlet passage 34b. Thus air from the fan is directed in surrounding relation to the combustion chamber 8 of the head 1 and absorbs 35 and removes heat therefrom so as to prevent overheating of the combustion chamber. This air flows upwardly and forwardly around and in intimate contact with the head 1, thus providing one air wash and then passes into the main stream 40 from the fan.

Due to the walls 33 and 30, air from the fan is also directed around the outside of the head 1 and around the baffle wall 34 so as to provide a second air wash for preventing radiation of heat 45 to the walls 33. The flow of the first air wash stream, indicated by the arrows 38, passes around the combustion chamber 8, part passing outwardly through the passage 34a. The second air wash stream, indicated by the arrows 39, passes between 50 the wall 34 and the wall 33, by which it is directed to the front of the head 1. Thus a double air wash is provided to prevent radiation from the head and consequent heating of the outer decorative and supporting casing.

55 Above the level of the combustion chamber 8, the top wall 32 and side walls 33 terminate forwardly just in front of the wall 1a of the header, as better illustrated in Fig. 7, so that all air passing around the heat exchange head is directed 60 along the front wall 1a of the head and consequently is intermixed with the air issuing from the tubes 2.

Enclosing all of the apparatus described is a casing 40 comprising side walls 40a spaced from 65 the wall 33 and a rear wall 40b spaced to the rear of the fan 25. The rear wall 40b carries rearwardly extending flanges 41 which, at their rear limits, are formed to provide slideways 42 and which also define the air inlet passage to the fan. 70 A suitable filter screen 43 is removably fitted in the slideways 42 for filtering the air admitted to the fan, thus insuring cleaner air in the room being heated and also preventing combustible material from entering with the air and accumulat- 75

ing within the casing wherein it might become ignited or might char and create fumes within the room.

The casing 40 has a front wall 40c which, at its lower limit has an opening accommodating a drop door 45. The door 45 is hinged at its lower end so as to open by swinging downwardly forwardly, as indicated by the dot and dash line in Fig. 3, a suitable spring 46 and toggle connection 10 being provided for normally retaining the door in upright position. The outer casing 40 is provided with a floor 48 and depending legs 50. The rear wall of the casing extends below the level of the floor 48 and has air inlet openings 49 so that air from the room floor level may pass into that part of the casing lying below the casing floor 48. The legs 50 have passages 51 through which air from beneath the floor 48 may flow upwardly between the walls 33 and 40a, as indicated by the 15 arrows 51a. The door 45, in turn, is comprised of two walls spaced apart to form an air passage therebetween, the inner wall being provided with a series of air inlet passages 45a and, spaced thereabove and just below the level of the door 20 with passages 45b. Thus air from below the floor 25 48 is directed upwardly, as indicated by the arrow 45c, to provide an air wash between the walls of the door 45. Primary and secondary air for the burners is supplied through passages 48a formed 30 in the floor 48.

For assuring the proper flow of air around and over the head 1, deflectors 33a (see Fig. 6) are provided on the inner face of the side walls 33 of the inner casing so as to cause all air to be 35 deflected gradually toward and along the front wall of the heat exchange head. Correspondingly, on top of the heat exchange head are deflectors 52 which also serve the purpose of preventing concentration of heat in the corners of 40 the outer casing.

The casing is closed by a suitable top 53 which is preferably heat insulated and which swings upwardly, as indicated by the dotted line in Fig. 3, for permitting access into the interior thereof.

In order to provide the proper directional discharge of air from the casing the front wall 40c has an opening 40d which is substantially coextensive with and in alignment with the heat exchange head 1. Mounted within this opening and thus carried by the front wall 40c is a grill 60 comprised of a plurality of directional vanes 61 and an enclosing flange 62. The vanes 61 are sloped at an angle of about 15° to the horizontal in their normal position and are of such dimensions and spacing that the lower edge of each vane terminates above the plane of the upper edge of the next succeeding vane, thus providing projected clear spaces as indicated at X in Fig. 3. As a result there is no choking of the flow of air 60 or too great direct impingement thereof on the grill. The grill 60 is mounted in the front wall 40c for rotation about a horizontal axis extending forwardly and rearwardly of the head 1. Thus, if it is desired to deflect the air from the head downwardly, the grill 60 may be positioned as illustrated in Fig. 1. By rotating the grill 90° about its axis in Fig. 1 in a clockwise direction the air would be deflected to the left and if turned 180° the air would be deflected upwardly. An additional turning of 90° in the same direction deflects the air to the right. Thus the air may be deflected in any direction desired for obtaining the desired circulation, merely by rotating the grill 60. In larger units, the grill may be supported anti-frictionally on the wall 40c.

Generally, it is desirable to humidify the air preparatory to its discharge through the head 1 both for the purposes of maintaining the proper quality of air and for rendering the heating more efficient. For this purpose, there is provided near the bottom of the air inlet compartment 31, between the head 1 and the wall 30, a water receptacle 70. Preferably, the receptacle carries a header 71 which, as better illustrated in Fig. 4, has an air inlet passage 72 at one end, the air inlet passage being controlled by a suitable damper 73. For operating the damper 73, a suitable shaft 73a is gear connected thereto by complementary bevel gears 73b, this shaft, in turn, extending to the top of the apparatus and terminating in a 15 suitable indicator knob 73c. By turning the knob 73c, the amount of air passed through the 20 humidifying receptacle can be accurately controlled.

At its opposite end, the header 71 is provided with a deflectional hood 74 opening forwardly toward the head 1. The passage 72 is disposed so that the fan blades are turning theretoward. As indicated by the arrow 25a in Fig. 2, the normal tendency of the air within the air chamber 31 is to circulate downwardly toward the passage 72, along the top of the header 71 toward the hood 74, and upwardly at the opposite end. As a result, a higher pressure is built up adjacent the passage 72 than adjacent the hood 74 so that 25 the air flows through into the passage 72 through the receptacle and header 70 and 71 and out through an opening 74a beneath the hood 74. The outer surface of the hood 74 slopes in the direction of flow of the air theretop and thus 30 assists in creating a lower pressure zone at the opening 74a in the header 71. As a result, a continuous flow of air through the receptacle and in contact with water therein is assured. In order to assist in the evaporation and absorption 35 of water by the passing air stream, upright wicks 75 of absorbent material such as tufa rock and the like are mounted in the receptacle 70, the wicks extending from within the water in the receptacle 70 above the level thereof. In this 40 manner a much larger water evaporating surface is provided so that the air passing through the receptacle is humidified to the proper degree. A suitable filling spout 76 is provided in the receptacle so that water may be introduced by 45 hand if desired.

This structure makes possible circulation of a part only of the air from the fan into contact with the water and utilizes the slip stream of the 50 fan for effecting circulation.

In order to obtain the greatest efficiency, it is necessary that gas burners operate at their full rated capacity at all times while in operation. Consequently the burners 12 are so arranged that part of them may be burned at one time 55 or all of them operated simultaneously. Most general field conditions are met by having one pair of the six pairs of burners adapted for constant operation and four pairs adapted for operation only during higher heat requirements. Again, it is desirable that the rate of discharge 60 of air by the fan be correlated to the amount of heat supplied to the head 1 by the burners, the fan operating at lower speed and lower delivery when only part of the burners 12 are in operation and at higher speed and higher capacity when all burners are in operation.

It has been found that once a house or compartment has been heated to the proper temperature for comfort, much less heat is required 70 75

to maintain a temperature in the comfort zone if proper circulation is maintained. Heretofore, especially with natural circulation, when a predetermined temperature has been reached, the 5 source of heat has been entirely cut off or materially reduced with a consequent material decrease in circulation. Thereupon the air begins to stratify very rapidly, the heated air rising along the ceiling and the colder air settling along 10 the floor. As a result the room soon becomes uncomfortable while a few feet above the floor level the air is adequately warmed and, in fact, is too warm for comfort. With the present structure, once the proper temperature has been 15 obtained, the heat supply is reduced materially but circulation of the smaller quantity of heated air only sufficient to replace the heat actually lost and to prevent stratification is provided. Much of the heat supposedly lost from a room 20 is not lost but merely is located in the upper strata. With the present heater, the air is constantly drawn from the floor level, warmed appreciably and then discharged, thus affording constant circulation free from stratification so 25 that the air which normally lies along the ceiling and is ineffective flows or is forced down to the zone normally occupied by the occupants of the room. For accomplishing this result and rendering the structure entirely safe, the following 30 control system is provided, and best illustrated in Fig. 5.

In the bottom portion of the outer casing is a main gas inlet 80 which leads to a gas pressure regulator 81 of the diaphragm operated type 35 from which extends the main feed line 82. The main feed line 82 is provided with a control cock 82a which is manually operated.

Beyond the cock 82a, the line 82 is connected to a thermostatic cutoff valve 83 which, in turn, 40 is connected to a suitable Y-connection comprising branches 84 and 85, the valve 83 being operable when closed to block the flow of gas to both branches. The branch 84 leads to the upper compartment 86a of a gas manifold which compartment supplies gas to the central pair of burners 12. The branch 85 leads around the burners to the rear of the casing to a main solenoid control valve 87 which is connected to a feed line 88 leading to the lower portion 86b of the 45 gas manifold. The lower portion of the gas manifold supplies only the two outermost pairs of burners, the gas supply thereto being under the control of the solenoid valve 87.

Connected in the line 82 in advance of the cock 50 82a is a by-pass conduit 89 controlled by a suitable stop cock 89a. The conduit 89 supplies gas to the primary pilot light 90, the flow of gas thereto being controlled accurately by an adjusting needle valve 90a. The pilot 90 is for 55 igniting the service burners and is preferably in the form of an elongated tube having a series of jets arranged in a row lengthwise so that they terminate at the lower end adjacent a supplemental control pilot 91. Arranged in heating 60 relation to the pilot 91 is a bi-metal thermostatic bar 92 which is responsive to temperature changes of the pilot 91 and operates the cutoff valve 83, cutting off the supply of gas consequent upon the supplemental pilot 91 becoming extinguished for an interval.

For supplying gas to the supplemental pilot 91, a gas conduit 93 is connected to the line 82 through the valve 83 in advance of the valve plug, so as to receive gas continuously from the 65 line 82 when the cock 82a is open. The tube 93

extends beneath the burners and up along the side of the outer casing interiorly thereof to the top of the apparatus wherein it is connected to a manually controlled cock 94. Leading from the cock 94 is a return line 95 which leads to the supplemental pilot 91 so that the pilot 91 can be turned on and off by hand. Connected to the line 88 is a gas pressure operated diaphragm switch 97 having electrical contactors 97a for effecting an electrical connection, later to be 10 described, consequent upon admission of gas into the line 88 by the solenoid 87. Both in solenoid valves of this type and in pressure regulators employing a diaphragm, gas may escape past the diaphragm and into the room, and to prevent this, 15 a suitable conduit 98 is connected both to the switch 97 and pressure regulator 81, as better illustrated in Fig. 2, and leads to a bleeder conduit 99, which leads into the exhaust stack of the apparatus. 20

For operating the burners in accordance with room temperatures, the solenoid valve 87 is connected by suitable conductors 100 and 101 respectively to a room thermostat and to one side of a 110-volt A. C. circuit, a suitable wall socket 25 100a being mounted on the rear of the apparatus for rendering a connection of the thermostat more easy. The solenoid may be operated directly on a 110-volt circuit or a suitable step-down transformer may be provided, if desired, 30 so that the solenoid operates on lower voltage. Also leading from the same side of the 110-volt circuit as the conductor 101 is a conductor 102 which leads to one post of a reactance control of the fan motor 26. One post of the fan is 35 connected to the control resistance 103 through a binding post 104. The control has also a shunt binding post 105 so that the resistance may be shunted for effecting higher speed of the fan. The binding post 105 is connected to a suitable conductor 105a which leads to one contactor 91a of the switch 97 and continues by a conductor 105b to the same side of the 110-volt line as the conductor 102, preferably by connecting conductors 102 and 105b at the resistance 103. Thus 40 when contact is made through the switch 97, the current flows around all or part of the resistance 103 and the fan may operate at greater speed than when the current must pass through the entire resistance 103, as is the case when the 45 switch 97 is open. 50

As explained it is necessary to open the valve 94 in order to operate the supplemental pilot and admit gas to any of the burners. The valve 94 also carries an electric switch having a movable 55 blade element 110, connected to the opposite side of the 110-volt A. C. circuit from the conductor 102 by a conductor 110a, and which, when the valve is turned to admit gas to the supplemental pilot, connects the circuit through conduits 110a 60 and 111. As better illustrated in Fig. 7, the conductor 111 leads to a suitable plug fuse 112 and from this plug to the other pole of the motor 26. Thus when the valve 94 is open, the supplemental pilot operates, heating the bi-metal 92 65 and opening the valve 83, at the same time closing the circuit through the motor and all of the resistance 103 so that the motor runs at low speed. The room thermostat 113 is connected in the circuit by the conductor 100 and a conductor 70 114 and conductor 111 and when it closes, completes a circuit through the solenoid valve 87 75 so that the valve opens, admitting gas to the pressure operated switch 97a. At the same time it admits gas through the conduit 88 to the outer 75

pairs of service burners. This pressure operates the switch 97a closing the circuit which shunts out a large part of the resistance 103 so that the motor operates at high speed.

5 The specific operation can be more fully understood by an exemplary description thereof in connection with Fig. 7. Referring to this figure and Figs. 1 and 5, the operation is as follows: the stop cock 89a is opened and the pilot 90 is lighted. Next the cock 82a is opened admitting gas to the valve 83 which is now closed. In this condition the apparatus may remain indefinitely ready for actual use. When heat is desired, the cock 94 is opened and admits gas to the supplemental pilot burner 91 which heats the thermostatic bi-metal 92 and opens the valve 83. The operation of the switch 94 for this purpose closes a circuit so that the fan operates at low speed. The opening of the valve 83 also admits gas to the solenoid valve 87 at which point it is blocked. Heat is supplied only by the center pair of burners 12. When more heat is required, the thermostat 113 closes, completing a circuit through the solenoid 87 which opens and admits gas through the conduit 88 to the outer pairs of burners so that all burners are operating. At the same time, it admits gas to the valve 91. The gas pressure closes the circuit through the contactors 97a, thus connecting the fan with the resistance 103 partially or fully shunted out, depending on the connection provided. As a result, concurrent increase in the speed of the fan and ignition of the outer sets of burners is effected. After this operation is completed, the 35 larger volume of heat is supplied until the room thermostat 113 again breaks the circuit at which times only the central burners operate and the switch 97 opens thus cutting the fan to low speed. This condition is continuous until the room thermostat again operates to demand more heat.

It might be that in some manner the fan is prevented from operation, in which case the structure would become overheated. Such heat, however, before endangering the apparatus destroys the fuse plug 112 and breaks the circuit so that the solenoid closes and only the central set of burners operate. The central burners alone are not sufficient to overheat the exchanger and other apparatus even when the fan is not operating, so complete safety is assured.

Having thus described our invention, we claim:

1. In an air conditioning apparatus, a combustion chamber, a heat exchanger superimposed thereon and in communication therewith, a fan at the rear of and spaced from the exchanger for supplying a stream of air, a casing surrounding the chamber, exchanger and fan with its walls in spaced relation thereto, and having a discharge

passage in front of the exchanger, a baffle in the casing surrounding the chamber and spaced therefrom and from the casing walls and having an inlet opening admitting air from the fan, and a discharge opening remote therefrom, a baffle in the casing surrounding the exchanger and said first baffle in spaced relation thereto and to the said casing for receiving air from the fan, and having a discharge passage in front of the exchanger, and means for admitting air between 10 the second baffle and walls of the casing.

2. In an air conditioning apparatus, a combustion chamber, a heat exchanger superimposed thereon and in communication therewith, a fan at the rear of and spaced from the exchanger for supplying a stream of air, a casing surrounding the chamber, exchanger and fan with its walls in spaced relation thereto, and having a discharge passage in front of the exchanger, a baffle surrounding the chamber and spaced therefrom and from the casing walls and having an inlet opening admitting air from the fan, and a discharge opening at the front, a firing door in the combustion chamber aligned with said opening, and a second baffle in front of said discharge opening 25 and spaced from the first baffle and from the casing and having an opening aligned with the discharge opening in the first baffle, a door on said second baffle for closing the opening in the second baffle, and means to admit air from the 30 fan between the said baffles whereby said air may flow from between the baffles through the opening in the first baffle and air wash the firing door.

3. In an air conditioning apparatus, a combustion chamber, a heat exchanger superimposed 35 thereon and in communication therewith, a fan at the rear of and spaced from the exchanger for supplying a stream of air, a casing surrounding the chamber, exchanger and fan with its walls in spaced relation thereto, and having a discharge 40 passage in front of the exchanger, a baffle surrounding the chamber and spaced therefrom and from the casing walls and having an inlet opening admitting air from the fan, and a discharge opening at the front and being open at the top 45 for discharge of air, a firing door in the combustion chamber aligned with said discharge opening, and a second baffle in front of said discharge opening and spaced from the first baffle and from the casing and having an opening aligned with 50 the discharge opening of the first baffle, a door on said second baffle for closing the opening therein, and means to admit air from the fan between the said baffles whereby said air may flow from between the baffles through the opening 55 in the first baffle and air wash the firing door.

GEORGE HERBSTER.
JOSEPH BECVAR.
